KNITTED FABRIC

Henry Harold Helmes, Leicester, England, assignor to Wildt and Company Limited, Leicester, England, a British company

Application November 2, 1937, Serial No. 172,482
In Great Britain November 3, 1936

2 Claims. (Cl. 66—172)

This invention relates to knitted fabrics and articles, such, for example, as stockings, half-hose, socks and rib tops, and concerns fabrics and articles split across the wales, i. e., in a circumferential or coursewise direction in the case of a knitted tube to form partially separated sections.

It is known to provide fabrics or articles of this character wherein the separation of the fabric sections is due to partial unravelling of a course or cutting of the wales, but as far as I am aware both of the resultant edges have been overlocked or stitched to prevent running of the disconnected or severed wales and provide a finished appearance.

The disadvantage with overlocking or stitching is that if it is not done carefully the said edges are rendered unsightly and this consequently detracts from the appearance of the finished fabric or article.

The present invention has for its object to produce a fabric or article of the character described of an improved appearance as regards the finish of at least one of the aforesaid edges.

According to this invention there is provided a knitted fabric or article having partially separated sections at least one of which has a no-run edge or stitch portion which is produced in a finished condition.

By a no-run edge or stitch portion produced in a finished condition I mean a selvedge edge or portion which is produced by means of the machine on which the fabric or article is knitted in contradistinction to an edge or portion overlocked or stitched subsequently to the knitting of the fabric and partial separation of the sections, by means of an overlocking or sewing machine.

The present invention is distinguished from the known fabric in that when separation of the fabric sections is effected one at least of the edges thus produced is in a finished condition and requires no further treatment.

The invention may be carried into practice in a knitted fabric or article wherein one or both of the sections formed by the separation have elastic thread incorporated as, for example, in a garter section of a stocking, half-hose, sock or like article or a rib top therefore, as well as in a fabric wherein the sections are made wholly of relatively inelastic yarn. When elastic thread is provided in the fabric it may be incorporated in every course or at intervals of one or more courses, according to requirements.

In the accompanying drawings:

Figure 1 shows so much of a knitted article, e. g., a half-hose as is necessary to illustrate the application thereto of the present invention.

Figure 2 is a view somewhat similar to Figure 1 showing a modification.

Figure 3 purports to represent an enlarged face or front view in diagrammatic form of the portion of fabric enclosed by the dot-and-dash lines A in Figure 1, the said portion being shown as it appears before partial separation of the article sections has been effected.

Figure 4 is a similar view of a modified portion of Figure 3 showing how the article may be made with a draw thread so as to facilitate partial separation.

Figures 3 and 4 are of course, drawn to a larger scale than Figures 1 and 2 and like parts are designated by similar reference characters throughout the drawings.

Referring to Figure 1, it will be seen that the article is split at 1 in a circumferential direction to form partially separated sections 2 and 3. The portion of the article illustrated purports to represent a ribbed top and the separation is effected so that the section 2, i. e., the garter section, may, when the article is worn, assume an angle with respect to the remaining portions of the article, or in other words assume an angle which is ordinarily assumed by the garter in common use. In the specific example now being described a machine made selvedge or the like, that is to say a no-run edge which is produced in a finished condition, is provided at the edge 4 which is further away from the end 5 of the article at which knitting is commenced. The edge 6 opposite to the machine made selvedge or the like is not finished as produced on the machine but is subsequently overlocked or otherwise stitched when the article is taken off the machine to provide a finished appearance and the said machine made finished edge 4 is constituted by a part of a welt 7 which extends all round the article. The article shown in Figure 1 is also formed for a purpose herein-after to be explained, with a welt 8 which also extends all round the knitted tube above the welt 7. As will be appreciated the welt produces at a a ribbed or beaded effect across the fabric which is unaffected by the partial separation, which effect appears to break the continuity of the fabric and renders the appearance of the garter section 2 more pronounced.

As already alluded to, however, the welt may, as shown in the modification illustrated in Figure 2, be limited to the extent of the partial separation 1 in which case the remaining con-

tinuous fabric retains its ordinary unbroken characteristic appearance. In Figure 2 the machine made finished edge 4^a is constituted by a partial welt 9 extending from one end of the split 5 1^a to the other and the article is formed with another welt 10 of like extent, leaving the front portion b of the ribbed top of the article unbroken in its appearance.

Referring now to Figure 3, it will be seen that 10 in the article illustrated in Figure 1 the co-extensive adjacent welts 7 and 8 are initially joined by a course of loops 11 which is shown lightly shaded for the sake of clarity. In a portion 15 of this course corresponding in extent to that of the split 1 to be made subsequently, some of the loops, e. g., alternate loops such as those indicated at 12, are cast off leaving the remainder of the loops such as 13 in said portion to join the fabric sections 2 and 3 until partial 20 separation is to be effected, for example by cutting the joining loops along the line c. It will thus be appreciated that when the loops 13 are cut, the edge 4 of the section 3 presents a perfectly finished appearance by reason of the fact 25 that all of the loops of the welt 7 are locked in the fabric. With regard to the welt 8, however, this does not present a finished appearance for the reason that some of the loops thereof, i. e., the loops 14 through which the cast off loops 12 30 are drawn, are not locked in the fabric but are free to run back when the joining loops 13 are cut. The welts shown in Figure 3 are ordinary roll welts produced in the usual way by suspending knitting for the desired number of courses 35 on one series of needles, i. e., the rib needles, so that rib loops such as those indicated at 14 are stretched and joined to the rib loops of a subsequent course. The two adjacent welts may be of any suitable length. The advantage of forming 40 two welts is that when partial separation of the fabric sections is effected, the welt 8 restricts running back of the cast-off wales and facilitates subsequent finishing of the edge 6 by overlocking or the like after the article has been removed 45 from the machine. If desired, instead of forming a single course of loops 11 as aforesaid, two or more such courses may be formed for the same purpose between the two welts.

Moreover, instead of providing a partial course 50 including cast off loops such as 12 (Figure 3) a draw thread 15 of a like extent may be inserted temporarily to hold the fabric sections 2^a and 3^a together as represented in Figure 4. In this instance partial separation of the fabric sections 2^a 55 and 3^a can be readily effected merely by the removal of the draw thread.

The invention may be applied to flat knitted fabric, but it is principally intended to apply it as just described to circular knitted fabric in 60 which case the partial separation may, as shown in Figures 1 and 2, be effected to the extent of substantially one half or a little more of the circumference of the knitted tube. In the application of the invention to an article such as a 65 rib top, stocking, half-hose, sock or the like, to produce a garter top or section such as 2 the partial separation is effected round the back of the knitted tube in the required locality in a walewise direction.

70 Broadly considered, the method of producing the required effect includes, after the required number of ordinary courses, e. g., rib or plain, a change in the knitting action whereby the machine made selvedge or no-run course or stitch 75 portion is produced, and then continuing to knit

in the ordinary manner to complete the production of the fabric or article required. The aforesaid change may be preceded by the knitting of a separating course in which some, e. g., alternate needles of a group of consecutive needles 5 are caused to cast off loops, or by the feeding of a draw thread instead of the main thread to the said group of needles.

A specific method will now be described with reference to the drawings. This method includes, after the formation of a required number of conventional plain or rib courses, such as the 1/1 rib courses indicated at 16 in Figure 3, knitting a welt such as 8, then resuming ordinary knitting for a course or courses such as that shown at 11 but casting off some of the loops 12 of a series corresponding in extent to the extent of the separation required thus leaving joining loops such as 13, or alternatively introducing a draw thread to the same extent as 20 shown in Figure 4, then knitting another welt such as 7, then resuming ordinary knitting for as long as required, subsequently effecting separation of the fabric sections 2 and 3 by cutting the loops 13 at c or pulling out the draw thread, 25 as the case may be, and overlocking the upper of the two edges 4 and 6 formed by the partial separation thus effected.

When the fabric sections are ribbed they may be of 1/1 or any other desired rib combination. 30 If desired, they may be of a fancy ribbed character. In the event of the fabric sections being plain knitted, they may also be of a patterned or fancy character. Alternatively, the upper or garter portion may, in the case of hosiery, be 35 of a different character of knitting from the remaining or leg portion.

It will be understood that the invention may be applied to rib tops produced singly or in strings for transfer subsequently to the needles 40 of other machines adapted to produce leg and foot portions of stockings, half-hose, socks and the like, or for attachment to independently knitted leg and foot portions by a linking machine, as well as to stockings, half-hose, socks 45 and like articles produced with tops and leg and foot portions produced in a continuous operation on one and the same machine.

The knitted fabric or articles may be produced on any knitting machine suitably adapted 50 for the purpose and preferably having two sets of needles, but it is mainly intended to employ circular knitting machines, for example, of the cylinder and dial type, or of the double axially opposed needle cylinder type, for example, machines 55 of the characteristic type having superposed needle cylinders and double ended needles operated by means of sliders, as exemplified in prior British Specification No. 15,008 of 1900, and No. 24,290 of 1912, such machines being equipped with 60 means such as welt cams and controlling mechanism therefor, for producing the required selvedge effect on the needles or selected needles, and if desired with means for causing prearranged needles to cast off, or with means for introducing a draw thread, according to requirements.

When elastic thread is to be incorporated in the fabric as, for example, in the production of stockings, half-hose, socks and the like with a garter section or top, the said thread may be incorporated in the form of straight wefts or in the form of loops or stitches, in combination with another inextensible thread. Alternatively, the whole of the garter section may be formed entirely of elastic thread.

A machine having a single feeder or two or more feeders may be employed, and when elastic thread feeding means are provided the same may be of any conventional form and arranged or/and operated so as to feed the thread to the needles at every course or at intervals of two or more courses during the production of an elastic section. For example, the said means may operate continuously or intermittently in a single feeder machine during the production of an elastic section, and in a two feeder machine may be located at one feeder and operated continuously or intermittently, or may be arranged at alternate or other desired feeders in a machine having more than two feeders.

The term "fabric" hereinafter used in the appended claims is intended to include knitted articles and parts for incorporation into such articles.

What I claim then is:

1. A finished knitted fabric split between its ends in a coursewise direction thereby providing partially separated sections and comprising initially co-extensive adjacent welts, and at least one course of knitting for joining said welts, some of the loops in a portion of said course corresponding in extent to that of the split to be made subsequently being cast off while the remainder of the loops in said portion join the fabric sections until partial separation is to be effected. 5

2. A finished knitted fabric which is split between its ends in a coursewise direction thereby providing partially separated sections and comprising initially co-extensive adjacent welts, and a temporarily inserted draw thread of an extent corresponding to that of the split to be made subsequently, said draw thread serving to hold the fabric sections together until partial separation is to be effected. 10 15
